UNITED STATES PATENT OFFICE.

CHARLES R. DAELLENBACH, OF ALLEGHENY, ASSIGNOR, BY DIRECT AND MESNE ASSIGNMENTS, OF TWO-THIRDS TO RUDOLPH GLASSER AND HENRY SCHOENEFELDT, OF PITTSBURG, PENNSYLVANIA.

RAILWAY-SWITCH.

SPECIFICATION forming part of Letters Patent No. 417,156, dated December 10, 1889.

Application filed July 24, 1889. Serial No. 318,574. (No model.)

To all whom it may concern:

Be it known that I, CHARLES R. DAELLENBACH, a citizen of the United States, residing at Allegheny, in the county of Allegheny and State of Pennsylvania, have invented certain new and useful Improvements in Railway-Switches; and I do declare the following to be a full, clear, and exact description of the invention, such as will enable others skilled in the art to which it appertains to make and use the same.

This invention relates to certain novel and valuable improvements in devices for automatically operating railway - switches, by means of which the engineer can change a switch for a siding or a main track, or vice versa, at will, and at the same time cause a signal to appear indicating "danger" or "safety," as will be fully understood from the following description, taken in connection with the annexed drawings, in which—

Figure 1 is a side elevation of a locomotive-engine of the well-known kind having my improved devices applied to it for enabling the engineer in his pilot-house to actuate the device which switches the rails and moves the signals. Fig. 2 is a vertical longitudinal section of the steam cut-off and reverse twin cylinder and valves, showing the tubular ports between these cylinders, a portion of the lower hand-rod being broken away. Figs. 3 and 4 are views in detail of the hand-levers used to operate the valves in the twin cylinders shown in Figs. 1 and 2. Figs. 5 and 6 are details of the said hand-levers, showing the locking or clutching faces for the levers. Fig. 7 shows the spring on the bolt in detail for holding the said clutches together. Fig. 8 is a vertical central section showing the vertical steam-cylinder and its attachments, by means of which the engineer can actuate certain levers on the track for shifting the switch. Fig. 9 is a top view of the lower portion of piston-guide for the vertical cylinder, the latter being removed. Fig. 10 is a top view of one of the levers or spiders on the rail-track and a portion of the switch-actuating cable applied to a pulley thereon. Fig. 11 is a side elevation of Fig. 10. Fig. 12 is a sectional view of the lower part of Figs. 10 and 11, showing a spring-bolt for holding the said

lever or spider by a friction-clutch in operative position. Fig. 13 shows in a top view what I denominate the "three-armed swinging beam" and its "spider base-plate." This figure also shows the laterally-movable spring-recoil or switch-bar connected by a slot and pin to one of the limbs of the said beam. Fig. 14 shows a bottom view of the lever of Figs. 10 and 11. Fig. 15 is a detail top view, with cover removed, of the connecting switch-bar which is applied between the free ends of the switch-rails, showing the two helical springs and adjusting-nuts for regulating the tension of the wire cables and keeping them under proper tension under different temperatures. Fig. 16 is a plan view of a railroad-track, showing main and siding tracks and a switch, together with a transverse bar connected to a signaling device arranged in the usual well-known manner, and having my improved shifting-levers and cable-connections applied adapted to be operated by a device on a locomotive. Fig. 17 is a vertical cross-section enlarged, partly in section through the track, taken at the point indicated by dotted line *xx* on Fig. 16, indicating the devices for automatically signaling to the engineer of an approaching train the exact position of the switch-rails with respect to the main-track rails. Fig. 18 is a detail front elevation of the disk. Fig. 19 is a vertical central section through the top of my signaling device, taken in a plane at right angles to the sectional plane of Fig. 17. Figs. 20 and 21 show two views of a wrench which is adapted for use in operating the switch by hand independently of the device on the locomotive.

Similar letters of reference indicate similar parts throughout the several figures.

Referring to the annexed drawings by letter, A designates a locomotive of any well-known construction. On each side of this locomotive I apply my improved devices for moving the switch-rails, hereinafter explained, the said devices being alike on both sides. A' designates a plate or suitable frame, which is bolted to the boiler shell or casing near the pilot-house, and to this plate A', I secure, in horizontal positions, two steam-cylinders A² arranged parallel to each other. These

cylinders have perforations 2 in their heads, as shown, for free ventilation. The upper cylinder is provided with a pipe a , leading from the steam-space of the steam-dome A^4 ; also with a pipe a' , which leads to the smoke-stack, for carrying off the exhaust-steam. Inside of this upper cylinder A^2 are three packed pistons $a^2 a^3 a^3$, or valves, secured equidistant from each other on an endwise-movable rod a^4 . The lower cylinder A^3 is also provided with three pistons or valves, fast on an endwise-movable rod, and both cylinders are connected by short pipes $b b'$, one b being used for conducting live steam from a chamber X into a chamber X' , and the other serving for conducting exhaust-steam from a chamber X^2 into a chamber X^3 , from which latter the exhaust-steam escapes through the pipe a' to the smoke-stack. Pipes a^5 , leading from the bottom of the two steam-cylinders $A^2 A^3$, communicate with pipes at the upper end of vertical steam-cylinders B , one of which is shown clearly in the sectional view, Fig. 8, and represented in position in Fig. 1, and hereinafter fully described. Each one of the valve-rods a^4 of the steam-cylinders $A^2 A^3$ extends back into the pilot-house and is pivotally connected to a hand-lever B' , which is connected to a spider B^2 , secured to the boiler-shell by means of bolts c . The spider B^2 and the lever B' have circular hubs $c' c^2$ formed on them, the impinging faces of which are radially serrated, forming a friction clutch or lock for holding the lever in any desired position. By means of a coiled spring c^3 , (indicated in Fig. 4,) applied in a recess in the hub c' of spider B^2 , and a nut c^4 on the bolt k' , the clutching-faces of the two hubs are held together with sufficient friction to prevent the lever from casually slipping after it is adjusted.

I employ a cylinder B and its attachments on each side of the bed of the locomotive. Each cylinder B is bolted to a substantial base-plate or flanged head re-enforced by flanges and rigidly secured to the bed-frame of the locomotive in the position shown in Fig. 1.

Extending down from the re-enforced portion of the base-plate B^3 is a tubular guide B^5 , which is slotted at d , for the purpose of receiving a cross-head C' , which passes diametrically through a piston-rod B^6 and is suitably secured therein, and which also passes freely through the vertical slots d and is guided thereby. This piston-rod has secured on its upper end a piston B^7 , suitably packed, and on its lower end is applied a concave switch-mover C , held freely to this piston-rod by screws or pins d^7 beneath the shouldered portion of the rod. It will be observed by reference to Fig. 8 that the mover C is free to rotate about the reduced portion of the piston-rod, so that when it strikes a device on the roadway, hereinafter described, there will be practically no jar or concussion, for

the reason that it will turn freely about said reduced portion.

On the lower end of the slotted guiding-tube B^5 are applied two eyes $d^2 d^2$, and between these eyes and the cross-head C is applied a helical spring d' , the object of which is to lift the piston B^7 after the steam-pressure above it is removed and exhausted.

By reference to Fig. 1 it will be seen that the eyes d^2 on the lower part of the guide-tube B^5 are secured to stirrups D , which are bolted to beams D' , forming parts of the bed-frame of the locomotive. The operation of this part of my invention is as follows: At a proper time before the train reaches a switch, if the signal-light indicates that the switch-rails are not in proper position either for the main track or the siding, the engineer allows steam to enter the proper cylinder B by adjusting the levers above described. This depresses the piston and its rod B^6 and causes the corresponding switch-mover C to be brought into such relation to certain switch-levers, hereinafter described, that they will impinge thereon and change their positions without undue shock. After crossing the switch the engineer, by a simple manipulation of the levers above described, cuts off the live-steam pressure from the boiler and allows the spring d' to lift the piston and the switch-mover C out of the way; or he may leave the switch and signal as it was found on his approaching it, the signal hereinafter explained always indicating to an engineer on an approaching train the positions of the switch either for the main track or for the siding.

I will now proceed to describe the improved devices which I apply to a railway-track at and near the switch-rails or siding and signal-station. Fig. 16 shows a portion of a main track, a siding, and a switch, together with my improved appliances, which are designed to be operated by the devices above described. E E designate the main-track rails; F F, the side-track rails; G G, the switch-rails; J J', the cross-ties, all of which may be constructed and laid down in the usual well-known manner.

At suitable distances apart I arrange certain two-throw levers K , which are preferably made in the form of the figure 8, as shown in Figs. 10, 14, and 16. On the main track and on one side of the signal-supporting cross-tie J' , I show three of the said figure-of-8 levers K , which in practice are arranged at long distances apart, and on the opposite side of said cross-tie J' , I show only a single lever K . I also show three of these levers K arranged as follows: one near the switch-rails at G'' and two on the siding-track. These levers are all arranged between the rails, or preferably in the center of the track, so that they shall be struck and operated by the switch-turner C on either side of a locomotive moving toward the signal or switch station from the right hand or the left, as the

engineer may desire. Each lever K is provided on its lower side with a pulley or cylindrical hub p^2 , having radial serrations s , adapted to engage with similar serrations s' , formed on the upper side of a spider K', which latter is rigidly secured to the cross-ties J. Through the said lever and spider-hub passes a bolt k , which receives a nut on its lower end, and also a locking-spring s^4 to prevent the nut from turning backward and working loose, and which is seated inside of the spider K', and also tends to hold down the lever K, but allows it to be shifted about its vertical axis either to the right or left. I thus apply to each lever K a friction-clutch which will positively hold the lever after adjustment, but allow it to be shifted about its axis when struck by the device C, above described.

It will be observed that I employ ropes or cables V for the pulleys of the levers K on the main track, and also for the similar pulleys of the levers on the siding and switch rails. The cables V are attached to the pulleys p^2 by means of lugs m and knots k^4 , and the two cables are attached to the arms of a horizontal vibrating beam H^2 , which is pivoted by a vertical bolt e to a spider G^2 , secured to the cross-ties J. The arm G^2 of this beam H^2 is provided with a slot y^3 , which receives a vertical pin t , that passes through this slot and into a slot in the rod L. (Shown in Figs. 13, 15, and 17.)

L designates an equalizing-rod provided with a slotted yoke y' and collars $h' h'$. This rod is free to receive endwise play through guides $y y$, and between these guides and collars springs S^2 are compressed, the objects being to hold the yoke under equal right and left tension when the switch is in a normal position; also to prevent shock when the levers K are struck by the device C; also to compensate for expansion and contraction of the cables V. The rod L is connected by a link L' to the lower end of a T-shaped lever l' , pivoted to the hollow standard K of the signal by a horizontal pivot. (Shown in Fig. 17.) To the arms of this T-shaped lever l' are attached the lower ends of a rag-chain n , which passes over a flanged chain-drum n' , keyed on a horizontal shaft P, journaled in the upper part of the fixed half of the cylindrical signal-box N. The shaft P has suitably keyed on it inside of the walls of the box two circular plates T T, having perforations diametrically opposite each other and coinciding, as shown in Fig. 19, which perforations are covered with colored glasses R W, indicated "red" and "white," "danger" and "safety."

The cap of the signal-box is hinged at i on one side thereof, and should be provided with a suitable lock i' for preventing tampering with the interior of the box. Inside of this box is a stationary shelf or lamp-stand S, suitably secured to the fixed pedestal or to

the lower circular half of the signal-box and adapted to support a lamp L².

It will be seen that I employ, in combination with one or both disks, a stud j , which is designed to stop the illuminated disks in proper position with relation to the apertures through the sides of the hinged cap of the signal-box.

It will be observed from the foregoing, first, that if the engineer on a train moving on the main track toward the switch in the direction of the arrow (indicated in full lines, Fig. 16) finds the switch set for the siding by the red-light signal R, he will depress the right-switch turner C on that side of the locomotive, thereby shifting the switch for the main-track rail, as indicated in Fig. 16.

Should a train be approaching the switch in the direction indicated by the dotted arrow on Fig. 16, and the engineer desires to run on the main track, if the signal indicates "red" or "danger," he simply depresses the right-switch mover C and shifts the switch for the main track, leaving this track clear; or, again, when a train is running wild and is going on the siding the engineer can depress the right-switch mover and adjust the switch and signal so as to indicate to any train running on the main track the white signal, or "safety."

When it is desired to operate the switch and signal by hand, the key-lever shown in Figs. 20 and 21 may be used, one end of the pivotal stem l' being extended and squared to receive the socket of said lever, which should always be carried by the engineer in his cab.

Having described my invention, what I claim, and desire to secure by Letters Patent, is—

1. The combination, with a locomotive, of twin steam and exhaust devices, hand-levers for actuating the same, and vertical steam-cylinders provided with spring-actuated pistons having switch-rail shifters on the lower ends thereof, as specified.

2. The combination, with a locomotive, of the twin cylinders each provided with three pistons or valves and steam outlet and inlet pipes, the rectilinear movable valve-stems connected to hand-levers, the vertical steam-cylinders provided with pistons, the vertically-movable piston-rods provided with anti-friction switch-movers C, and lifting-springs for said pistons and rods, all as specified.

3. The combination, with the steam-cylinders, their pistons and rods, and the hand-levers for moving the same, of the pivotal bolts and serrated spring-actuated frictional clutches connecting said levers to their supports, substantially as specified.

4. The combination, with a locomotive provided with one or more steam switch-movers C, of twin cylinders having perforated heads for free ventilation, each cylinder being provided with three pistons and a rod and hand-

- lever for moving the same, and each cylinder being also provided with live-steam inlets and exhaust-steam outlets, as specified. 53
5. The combination, with a locomotive, of 5 cylinders having live-steam inlets and exhaust-steam outlets, and a vertical steam-cylinder communicating therewith, having a spring and steam actuated piston-rod provided with a rotative switch-rail mover, as specified.
6. The combination, with a locomotive and a switch-mover, of the twin steam-cylinders A² A³, the cylinder A² provided with a live-steam pipe a, and an exhaust-steam pipe a', the cylinder A³ provided with similar pipes, and both cylinders having perforated heads, and three pistons or valves connected to each hand-lever, substantially as and for the purposes specified. 65
7. The combination, with a locomotive having live and exhaust steam valves, of a vertical steam-cylinder provided with a spring-actuated piston having on its guide-rod a rotative switch-moving device C, as specified. 70
8. The combination, with a locomotive, of a vertical steam-receiving cylinder, a piston working therein, a piston-rod bearing on its lower end, a rotative switch-mover, a slotted tubular guide for said piston, a cross-head applied thereto, and a spring between the said cross-head and the eyes d, all as specified. 75
9. The combination, for the purpose described, of the steam-cylinder B, provided with a steam-inlet through its head, a perforated base B³, a vertically-slotted guiding-tube having eyes at its lower end, a cross-head C', freely movable in the slots of said tube and secured to the rod B⁶ of a piston B⁷, a switch-mover C on the lower end of said rod, and a recoil-spring between the said cross-head and eyes, all as specified. 80
10. The combination, with a bed-frame of a locomotive, of a stirrup D, and a vertically-movable steam and spring actuated piston having on the lower end of its rod a switch-mover, as specified. 85
11. The combination, with a main railway-track, a side track, and switch-rails, arranged substantially as described, of a system of two-throw self-locking levers arranged between the rails of said tracks and switch, a spring-surrounded lever adapted to switch the free ends of the switch-rails, and ropes or cables connecting said locking-levers to said lever, substantially as specified. 90
12. The combination, with the main track, the siding, and the switch-rails, of the levers K, provided with pulleys having lugs m m, the radially-serrated frictional locking devices, the spring-actuated bolt holding the said levers to their spider-supports, and the knotted cable engaging with said pulleys, as specified. 95
13. The open or 8-shaped levers having the serrated pulley-hubs p², in combination with the spider-bearing K, also having serrated hubs, the spring-actuated bolt, and a locking device for this bolt, substantially as described. 100
14. The combination, in a railway-track, as specified, of a series of automatically-locking levers adapted to be actuated by a switch-mover on a locomotive, a vibrating lever, the connecting cables therefor, and an operating spring-cushioned bar connected to the free ends of the switch-rails and to a signaling device, all as specified. 105
15. The combination, with the switch-rails, of the vibrating lever, actuated as described, having a slotted limb G², the signal-bar L, yoked and slotted, as described, the compensating springs S², and a signaling device connected by a rod or link L' to said bar L, as and for the purposes specified. 110
16. The combination, with the switch-rails, of the connecting-bars thereof actuated by levers and cables, as described, of the T-shaped lever l', the chain n, connected to the arms of this lever, the chain-pulley n', the perforated colored-light disks keyed on the shaft 90 of said pulley, and the signal-standard having a subdivided signal-box provided with a stationary lamp-stand, all as specified. 115
17. The combination, with a hollow signal-standard having a subdivided signal-box provided with perforations or windows through its hinged portion, of the oscillating disks provided with colored glasses, and a stationary lamp-stand, arranged as described. 120

In testimony whereof I affix my signature in presence of two witnesses.
